FUSE

Theodore Birkenmaier, St. Louis, Mo., assignor
to W. N. Matthews Corporation, St. Louis, Mo.,
a corporation of Missouri

Application November 16, 1931
Serial No. 575,193

10 Claims. (Cl. 200—117)

This invention relates to fuses, and with regard to certain more specific features, to throw-out fuses.

Among the several objects of the invention 5 may be noted the provision of a throw-out fuse which is adapted positively to pull at least a portion of a fuse link from a cartridge upon blowing thereof, and completely to disengage said portion from the cartridge; the provision of 10 means of the class described which may readily be attached to most of the cartridges now available; the provision of separate means adapted for use with fuses and cartridges of common construction which is simple in construction and operation. Other objects will be in part obvious and in part pointed out hereinafter.

The invention accordingly comprises the elements and combinations of elements, features of construction, and arrangements of parts which 20 will be exemplified in the structures hereinafter described, and the scope of the application of which will be indicated in the following claims.

In the accompanying drawings, in which are illustrated several of various possible embodiments of the invention,

Fig. 1 is a side elevation of a characteristic cartridge including the throw-out means of the present invention, the unbroken fuse element being shown in position;

30 Fig. 2 is a vertical section of the cartridge, etc., shown in Fig. 1, with the elements in their position at the instant the fuse link blows;

Fig. 3 is a bottom plan view of an expelling means shown in Fig. 1;

35 Fig. 4 is a section taken substantially on line 4—4 of Fig. 3;

Fig. 5 is a side elevation similar to Fig. 1 illustrating a modification of the invention, the fuse link being in unbroken condition;

40 Fig. 6 is a vertical section similar to Fig. 2, and illustrating the elements of the Fig. 5 modification in their position at the instant the fuse blows; and,

Fig. 7 is a section taken substantially along line 45 7—7 of Fig. 6.

Similar reference characters indicate corresponding parts throughout the several views of the drawings.

Broadly speaking, it has been shown to be decidedly advantageous to provide means, either in a fuse link or in the cartridge enclosing the fuse link, to separate, instantaneously, the two pieces of a broken fuse element immediately upon blow-out thereof. The advantage accrues in the fact 55 that arcing, sparking, and the like are positive-

ly and instantaneously inhibited. However, most of the prior devices constructed with such forcible expulsion means have been disadvantageous in that the lower or expelled portion of the fuse link, being directly connected to the connecting means of a cartridge, has, upon blow-out been permitted to dangle freely from the end of the cartridge in such position as to strike lower wires in a line installation or the like, thereby incurring the serious disadvantage of short circuiting. 60 Further, the lower end of the fuse link is ordinarily connected to an exposed connecting post on the cartridge, and, on account of corrosive action of the atmosphere, the connection has frequently become corroded to the extent that re- 70 placement with a new fuse link is quite difficult.

The present invention, recognizing the above difficulties, provides a means whereby all of the desired forcible expulsion advantages may be retained with the additional advantage, however, 75 that the lower portion of the fuse link upon expulsion is completely disengaged from the cartridge and allowed to fall freely, thereby minimizing danger from shorts and the like and leaving the cartridge in condition for immediate re- 80 placement with a new fuse link.

Referring now more particularly to Fig. 1, there is illustrated at numeral 1 the customary insulating material tube of a line-installation fuse cartridge. Numeral 3 indicates the upper connecting block of such cartridge, having a stud 5 adapted to clamp one end 7 of a fuse link 9 against a clamping surface 11 (see also Fig. 2). The fuse link 9 includes a fusible portion 13 so proportioned as to blow out or rupture upon the 90 passage of current in excess of a predetermined value. The fuse link 9 also includes a relatively long, relatively non-fusible connecting pig-tail or wire 15, which is preferably made of bendable material such as stranded copper wire or the like 95 flexible material.

Numeral 17 indicates the lower connecting block of the fuse cartridge assembly. The lower block 17 is provided with a stud 19, to which, in prior methods of using the cartridge, the 100 lower end of the connecting wire 15 was secured.

Numeral 21 indicates broadly an expulsion means comprising a strip of spring material, such as brass, which is also a good electrical conductor. The strip 21 has at one end thereof a hole adapted to receive and be removably clamped by the stud 19. On the other end of the strip 21 is formed an offset portion 23, by bending said strip 21 twice at right angles. Secured to the 110

off-set portion 23 (see Fig. 4) as by rivets 25 or the like is a square U-shaped piece 27, with the side arms extending at right angles to the plane of the portion 23. Mounted as by rivets 29 on the U-shaped piece 27 is a second U-shaped piece 31, the engagement of U-pieces 31 and 27 being such that they are free to rotate upon the rivets 29. Secured by rivets 33, similar to the rivets 25, to the U-piece 31 is an extension strip 35, which may be formed of the same material from which the strip 21 is formed. The strip 35 extends both sides of the U-piece 31 with a clamping end or tongue 37 adapted to rotate against the strip 21, and a longer end 39 (see Fig. 1). The longer end 39 has a lipped end 41, as illustrated in Figs. 1 and 3. The lip 41, while not essential, is desirable to preclude abnormal wearing of the connecting wire 15.

It will be seen that by means of the above construction, a hinged joint is provided between the strip 21 and the extension strip 35. Further, the clamping end or tongue 37 of the strip 35 is adapted, when properly tensioned, to clamp the end of the fuse wire 15 securely in position.

The assembly with the cartridges is illustrated in Fig. 1. It will be seen that the fuse link or element is clamped at the top with a stud 5, while the end wire 15 of the fuse element is brought out of the lower, open end of the tube 1 and clamped between the strip 21 and the extension 37 of strip 35. The strip 21, in its normal, untensioned position, is as shown in Fig. 2. Accordingly, when it is pulled to the Fig. 1 position, and there secured by the wire 15, it places said wire 15 under tension. Further, as the tension increases, the clamping force with which the end of wire 15 is secured or trapped is also increased. This makes for a tight, firm joint, with good electrical conductivity.

The assembly illustrated in Fig. 1 is then ready for operation. If, now, the fuse blows, the portion 13 separates, thus relieving the tension on the wire 15, and at the same time permitting the strip 21 to unbend with a snap action, thus whipping the wire 15, with the fragment of the fusible element 13 secured thereto, out of the open end of the tube 1. At the same time, since the strips 21 and 35 are no longer under tension, the clamping or trapping effect of end 37 against the strip 21 is relieved and the wire 15 is disengaged therefrom. This allows the wire 15 to fall freely and completely disengage itself from the cartridge. With a simple loosening of the stud 5, the remaining portion of the fuse element drops out through the tube 1, the cartridge is ready for the installation of a new fuse link.

A further advantage of the above construction is that the position of the strip 21, which is easily recognized at a considerable distance, indicates quickly and positively which of a number of cartridges has blown. Thus replacement is facilitated, as it is not necessary to test several cartridges in order to determine which one requires replacement. Furthermore, only one bolt needs to be loosened in order to effect a fuse replacement.

In Figs. 5, 6 and 7 is illustrated an alternative embodiment of the invention as applied to the same type of cartridge shown in Figs. 1 and 2. In this embodiment a strip of spring metal 45 is provided having a normal lateral configuration as shown in Fig. 6. The strip 45 is provided with an opening as at 47 (Fig. 7) to receive, and be clamped by, the stud 19. At the opposite end, the strip 45 is provided with a notch 49, which

leaves sidewardly positioned fingers 51. Somewhat below the upper end of the strip 45, a pair of tabs 53 are struck at right angles from said strip 45. These tabs 53 are bent to encircle, and form bearings for, a pin 55.

Swung rotatably on the pin 55 is a rigid element 57, comprising a central portion 59 having depending edges 61. The pin 55 passes through the opposite edges 61 and is bent at its outer end, to prevent it from falling out. At the lower end of the rigid piece 57 a finger 63 is struck, the finger 63 being adapted to slide into the notch 49 of the spring element 45. The edge portions 61 are extended to form fingers or tabs 65, which receive in a sliding fashion the fingers 51 of the spring portion 45.

With the device thus described secured to the cartridge by the stud 19, the wire 15 of the fuse element is brought out of the lower end of the tube 1, and is tied around the tabs or tongues 51 in such manner as to deform the spring strip 45 to the position shown in Fig. 5. The tie is such that a good electrical contact is effected between the wire 15 and the strip 45. The whole device is thus placed under tension of the bent strip 45, with electrical contacts being made to each end of the fusible element.

When, now, the fusible element blows, tension on the strip 45 is relieved and such strip immediately snaps to its relieved position illustrated in Fig. 6. In so doing, it whips the fragment of the fusible element out of the tube in position to be dropped. At the same time that the strip 45 resumes its unsprung position, the projection 63 and tabs 65 of the rigid element 59 are forced outwardly to their Fig. 6 position, thus pushing the knot portion of the wire 15 off the tongues 51 and thus completely disengaging said wire 15 and allowing it to fall freely to the ground.

Thus, with the embodiment shown in Figs. 5 to 7, a device is provided which not only whips the fragment of the fuse element from the cartridge, but also positively and effectively disengages the electrical contact of the end of said fuse element, and discharges it from the entire vicinity of the cartridge. The embodiment of Figs. 5 to 7 is advantageous in that it does not require the amount of space for installation that the Figs. 1 to 4 embodiment requires, and its disengaging action is more certain and positive.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. Throw-out means for a fuse cartridge comprising a resilient metallic strip adapted to be secured at one end to the side of said cartridge, means associated with said strip for securing said strip to a fuse link in said cartridge, thereby to bring the other end of said strip under tension and in proximity to the end of said cartridge, and means adapted to release said fuse link when the tension in said strip is relieved.

2. Throw-out means for a fuse cartridge comprising a resilient strip, one end of said strip being adapted for securing said strip to the side of said cartridge, an extension strip hingedly mounted on the other end of said strip, said ex-

- tension strip having a portion adapted to clamp against said resilient strip when the end of said extension strip is tensionably brought into proximity with the end of said cartridge. 50
5. Throw-out means for a fuse cartridge comprising a resilient strip, one end of said strip being adapted for securing said strip to the side of said cartridge, the other end of said strip having at least one finger formed therewith, and a piece hingedly mounted on said resilient strip, said piece having at least one notch thereon adapted to mesh with the finger on said resilient strip when said resilient strip is tensioned. 80
- 10 6. In combination, a tubular fuse cartridge having one clamping means at one end thereof and a second clamping means spaced from the other end thereof, a fuse link secured at one end to said first-named clamping means, and throw-out means secured to the second-named clamping means, said throw-out means comprising a resilient strip adapted tensionably to be bent towards said other end of the cartridge, and means associated with said throw-out means for securing the other end of said fuse link thereto, said last-named means being adapted to release said fuse link therefrom when said resilient strip is relieved of tension. 90
- 15 7. In combination, a tubular fuse cartridge having one clamping means at one end thereof and a second clamping means spaced from the other end thereof, a fuse link secured at one end to said first-named clamping means, and throw-out means secured to the second-named clamping means, said throw-out means comprising a resilient strip adapted tensionably to be bent towards said other end of the cartridge, and means associated with said throw-out means for securing the other end of said fuse link thereto, said last-named means being operable to secure said fuse link only when said strip is under tension. 100
- 20 8. In combination, a tubular fuse cartridge having one clamping means at one end thereof and a second clamping means spaced from the other end thereof, a fuse link secured at one end to said first-named clamping means, and throw-out means secured to the second-named clamping means, said throw-out means comprising a resilient strip adapted tensionably to be bent towards said other end of the cartridge, and means associated with said throw-out means for securing the other end of said fuse link thereto, said last-named means being adapted to receive and tensionably hold the other end of said fuse link. 110
- 25 9. Throw-out means for a fuse cartridge having contacts and a flexible fuse link therein joining with one contact to close a circuit, the throw-out means comprising a length of bowed spring material adapted to be secured at one of its ends exteriorly of the cartridge to electrically communicate with said circuit and means associated with said spring material for securing the same to said flexible fuse link while tensioning and bowing the spring material to position the securing end thereof adjacent to the end of the cartridge. 120
- 30 10. In a fuse switch of the character described, a cartridge comprising a tube, head and foot members on the upper end lower ends of the tube, a fusible conductor element housed within the tube and having its ends connected to said head and foot members, a flat spring strip having one end fixed on one of the members and its opposite end arranged to form a loop terminating in spaced relation with one end of said tube and tensioned by said conductor element for effecting withdrawal thereof from the tube upon fusing thereof. 130
